W. V. SEIFERT

DRILL COLLAR

Filed April 13, 1926

INVENTOR.
W. V. Seifert.

BY
J. J. DeLancey
ATTORNEY.

UNITED STATES PATENT OFFICE.

WILLIAM V. SEIFERT, OF DENVER, COLORADO.

DRILL COLLAR.

Application filed April 13, 1926. Serial No. 101,719.

This invention relates to drill collars and its principal object is to provide a practical; convenient and reliable medium for the connection of a drill bit at the lower end of a 5 drill pipe in rotary drills of the type used in sinking wells.

Another object is to provide a combination 10 of drill collar and drill bit by which the latter is held in its operative relation to the drill pipe so as to be readily removable and so that it may be adjusted to a limited extent for the purpose of cleaning or repair.

A further object of the invention is to provide in a combination of the above described 15 character, means for the passage of water to the cutting edges of the drill bit, in bits of the flat or fishtail type as well as in bits in which the cutters are mounted upon a supporting body, and still other objects reside in 20 details of construction as will appear in the course of the following description.

In the accompanying drawings in the several views of which like parts are similarly designated,

25 Figure 1, represents a sectional elevation of a drill collar in connection with a drill bit of the type in which rotary cutters are mounted on a supporting body,

Figure 2, a fragmentary section along the 30 line 2—2 Figure 1,

Figure 3, a bottom view of the drill bit shown in Figure 1,

Figure 4, an enlarged bottom view of the 35 collar of the construction shown in Figures 1 and 2, after the drill bit is removed,

Figure 5, a fragmentary longitudinal section of the collar shown in Figure 1, without the drill bit, drawn to an enlarged scale,

Figure 6, a section along the line 6—6 Figure 40 5,

Figure 7, a fragmentary side elevation of the collar and drill bit shown in Figures 1 and 2,

Figure 8, an enlarged section taken on the 45 line 8—8 Figures 1 and 2,

Figure 9, a fragmentary sectional elevation of a collar of modified form together with a drill bit of the fishtail type, and

Figure 10, a transverse section on the line 50 10—10 Figure 9.

Referring further to the drawings, the collar illustrated in Figures 1 to 8, consists of a hollow body 5, having at its upper end a screw-threaded nipple 6, for its attachment 55 in a correspondingly threaded socket at the

lower end of the drill pipe of the drilling tool (not shown in the drawings), and having its lower end enlarged to provide a flaring socket 7, for the reception of the drill bit.

The bit, as shown, consists of a body 8, 60 having at its lower surface bearings for the support of rotary sharp-edged cutting disks 9, which in the operation excavate the rock to form the well.

The body 8, has a reduced portion 10, fitting snugly within the lower end of the socket of the collar, made preferably in oval form, and centrally of said reduced portion, a flat shank 12, which in practice extends between two pairs of hollow bosses 13, in the 65 inside of the socket.

The shank is tapered to conform with the taper of the socket and it is provided with two slots 14, which register with the openings of the bosses at opposite sides of the 70 socket.

Extensions of the bosses at the outside of the collar are transversely apertured for the admission of locking keys or cotters 15, it being the purpose of the bosses, to support two 80 pins 16, which secure the drill bit in its operative position with relation to the collar.

The pins have transverse openings at one of their ends, which register with the before mentioned transverse openings of the bosses 85 exteriorly of the collar, and the cotters driven through the openings lock the pins against accidental displacement.

It will be observed that by the application of the pins as shown, and the fit of the drill bit 90 relative to the socket of the collar, the bit is maintained in operative relation to the drill pipe of the tool while it is readily removed or may be adjusted to the extent of the length of its slots for the purpose of furnishing a passage for water and mud around outside of bit in order that a sample of the formation may be taken in the hollow of the bit. Moreover, when the bit is plugged, by lifting drill pipe slightly off the bottom of the well, the water 100 is permitted to circulate around the body of the bit. This puts water in motion and by letting the drill stem down suddenly on the bit, the water delivers a blow on the plug which drives it from the bit. 105

The flat shank insures the rotative continuity of the drill bit with the collar and the drill bit is, as usual, axially bored to admit water introduced into the hollow collar from the drill pipe to the cutting disks. 110

In the form of the invention illustrated in Figures 9 and 10, the collar is constructed for the connection of a drill bit of the fish tail type.

5 The bosses on the inside of the collar 17, are omitted and the flat and tapering shank 18, of the bit 19, fits within the correspondingly shaped socket of the collar.

The shank is slotted as in the first described 10 form, and pins 20, passing loosely through the slots are, as before, supported in openings at opposite sides of the socket and held against displacement by cotters 21, extending in transverse bores of the pins and therewith registering apertures in bosses at the exterior of 15 the collar.

The bit is longitudinally fluted on both sides for the passage to its cutting edge of water fed into the hollow collar from the drill 20 pipe with which it is connected.

In both forms of the invention the drill bits are shouldered to engage with the lower end of the collar which thereby receives the impact of the engagement of the bits with the

work in the operation of the drill tool of 25 which it is a part.

Having thus described my invention, what I claim and desire to secure by Letters Patent is:

1. In a drilling tool, the combination with 30 a collar having a socket, of a drill bit mounted in said socket to move lengthwise with relation thereto, the bit closing the end of said socket in the operative position and providing a passage for water between the collar and the 35 bit in an inoperative position.

2. In a drilling tool, the combination with a collar having a water passage, of a drill bit mounted in said passage to move lengthwise with relation thereto, the bit closing the passage when in an operative cutting position and providing an outlet for water in the passage between the collar and the bit in an inoperative position.

40 In testimony whereof, I have hereunto affixed my signature.

45 WILLIAM V. SEIFERT.
